W. Fitzgerald

UNITED STATES PATENT OFFICE.

JOHN LEGAN, OF XENIA, OHIO.

SEALING DEVICE FOR FRUIT-JARS.

SPECIFICATION forming part of Letters Patent No. 398,633, dated February 26, 1889.

Application filed November 21, 1888. Serial No. 291,433. (No model.)

To all whom it may concern:

Be it known that I, JOHN LEGAN, a citizen of the United States, residing at Xenia, in the county of Greene and State of Ohio, have invented certain new and useful Improvements in Sealing Devices for Fruit-Jars; and I do hereby declare the following to be a full, clear, and exact description of the invention, such as will enable others skilled in the art to which it appertains to make and use the same.

My invention relates to improvements in devices for hermetically sealing fruit or other jars. This object I attain by means of the device herein described, and illustrated in the accompanying drawings. Such drawings are to be considered a part of this application, similar letters of reference referring to similar parts in both views.

20 Figure 1 is a side elevation of a jar, showing my improvements attached thereto. Fig. 2 shows the parts of Fig. 1 separated from each other.

A A are adjustable clamps, so bent as to somewhat resemble the letter S, having at their upper ends a hole, a', to receive the set-screw C. Such clamps A A also have a shoulder, a², which rests upon the lid of the jar, and loop a³ at their lower ends, intended for the purpose of receiving the adjustable band B, as shown. The adjustable band B is intended to fit snugly around the neck of the jar by means of the set-screw c, and fit into the loop a³ of clamps A A.

35 My invention is operated by adjusting the loop a³ around the adjustable band B at opposite sides of the jar and placing the set-screw C into position in screw-holes a', thus bringing the upper ends of clamps A A nearer together, and by such means cause a downward pressure of shoulders a² upon the lid of

the jar. A rubber band, yielding wax, or other suitable material, may be used under the rim of the lid.

I am aware that Letters Patent No. 365,592, 45 of date of June 28, 1887, were granted to one Gaynor for clamping device, which, on first inspection, might be regarded as having features in common with my invention; but a careful comparison of the two cases will at 50 once disclose the fact that a great difference exists, and especially in that part of the clamps resting on the lid of the jar, and referred to in my case as "shoulders a²." In the case of Gaynor, above cited, the part forming the fulcrum (the part resting on the lid of the jar) is so bent as to form an acute angle, while in my invention this corresponding part (shoulder a²) is so bent as to form almost a semicircle. I claim that the above-noted 60 difference produces results that make my invention greatly superior to that of Gaynor's. As instanced in my case, when the ends of the clamps are drawn together by the action of set-screw C, a yielding spring-like action is 65 produced throughout the entire clamp, while in the case of Gaynor the action is more rigid and is almost wholly confined to the fulcrum or shoulder.

Having described my invention, what I claim 70 as new, and desire to secure by Letters Patent, is—

The S-shaped clamps A A, in combination with set-screw C and adjustable band B, substantially as described, and for the purpose 75 named.

In testimony whereof I affix my signature in presence of two witnesses.

JOHN LEGAN.
